[57] ABSTRACT

A man-made island is located just off the coast to pro-

vide international airport and shipping facilities. The airport is located on the outer extreme of the island with runways paralleling the coast and extending in the direction of the prevailing winds. The sound contours drop off from the airport zone at the outer end of the island to a relatively low level at the inner end of the island close to the coast. The maximum height contour permitted by regulations increases in a direction perpendicular to the runways gradually so as to permit high-rise buildings at the end of the island closest to the coast. Industrial facilities which can tolerate a higher noise level and have lesser height requirements are located in the central portion of the island between the airport and the high-rise buildings. The airport area is raised significantly with respect to the main portion of the island. This provides additional safety against ocean surges toward the outer exposed end of the island and also permits easy access from the surface highways on the main portion of the island into underground tunnels and parking facilities in the airport area. Causeways extend from the mainland to the island at several points. In addition to providing highway and rapid transit access, the causeways may shield harbor and other facilities on the inner portion of the island from rough seas. The retaining caissons terminate below water level, and beaches are provided at the interface between the island and the water, and between the causeways and the water. These beaches provide recreation areas and a measure of safety for emergency landings and the like.

OFF-SHORE TRANSPORTATION, INDUSTRIAL AND URBAN COMPLEX

BACKGROUND OF THE INVENTION

Many proposals have been made heretofore for off-shore airport facilities. These have ranged from peninsular concepts to fully floating airports. Off-shore airports are desirable in minimizing the adverse effects of sound on nearby residents and in avoiding the necessity for purchasing large areas of adjoining property where building height restrictions and noise levels could cause problems. Up to the present time, however, it is not believed that anyone has proposed a complete off-shore island transportation complex including rail, highway and airport access, in combination with shipping facilities and associated industrial, residential and office high-rise buildings.

SUMMARY OF THE INVENTION

The invention primarily involves the organization or structuring of an off-shore island or peninsula for compatibility with a number of limitations associated with a major airport facility. The principal problems involved with a major off-shore facility involve (1) building height limitations, (2) noise level, (3) ocean water condition or exposure; and (4) surface elevation. The noise level is a critical factor. By locating the airport on the outermost portion of the island, the noise levels on the coast and at the inner edge of the island may be held to tolerable levels. Concerning maximum building height, the FAA regulations require that in the direction of the runways a 50:1 glide slope is required for an additional 25,000 feet. In the regions generally perpendicular to the runway, however, which is the direction that the island extends, within a 13,000 foot radius from the center of the airport the building height restriction is 150 feet. From this point a 20:1 slope permits increasing building height to 500 feet at a distance of an additional 7,000 feet. At the inner end of the island, therefore, high-rise buildings extending up to 500 feet or about 35 or 40 stories will be within this height limitation. High-rise residential and office buildings would therefore be located in this area of maximum height limitations and lowest noise levels. In considering the access to the island, causeways of solid construction extend to the middle of the island on at least one and preferably on both sides. These causeways have sloping beaches on either side, providing recreational areas. They also serve to block rough seas from harbor facilities located on that portion of the island which is inside the causeways, and from selected recreational areas located on the inner side of the causeways and on the sheltered coast of the island.

In accordance with another aspect of the invention, the island may be constructed of landfill behind retaining structures which extend from the ocean floor to a point well below the surface of the ocean. The surface contour of the island then includes beaches and rises to an elevation for the main inner portion of the island which is safely above high tide levels. The outer portion of the island, however, is at a substantially higher elevation to facilitate the access of highway traffic into the underground airport facilities. As noted above, the beaches around the island are provided for recreation and emergency airport safety reasons.

Other objections and features of the invention will be apparent from the following detailed description of the drawings in which:

FIG. 1 is a view of the off-shore island and associated coast and principal transportation features, in accordance with the invention;

FIG. 2 is an enlarged view of the island itself;

FIG. 3 is a diagrammatic showing of height and noise contours of the proposed complex;

FIG. 4 is a sectional view of the island taken along line 4—4 of FIG. 2, showing building height restrictions and variations in surface elevations of the island;

FIGS. 5 and 6 are cross sectional and plan views of the solid causeways providing highway access to the island;

FIG. 7 is a partial cross sectional view generally following FIG. 4 but showing certain features in greater detail;

FIG. 8 is a transverse cross sectional view taken along line 8—8 in FIG. 2; and

FIG. 9 is a partial cross sectional view showing the freeway and rapid transit vehicles as they may extend underneath the freeway in certain facilities included in the transportation complex.

Referring more particularly to FIG. 1 of the drawings, the island 12 is connected by a western causeway 14 and an eastern causeway 16 to the mainland which occupies the upper portion of the figure.

While the island could well be located in many other off-shore locations, it is shown in its relationship to the city of Long Beach, located in San Pedro Bay with the Pacific Ocean in the foreground. The existing breakwater 18 forms the inner boundary for the island 12.

The western causeway 14 is shown connecting with the Harbor Freeway 20 and the eastern causeway 16 is shown connecting with the San Gabriel River Freeway 22. A third transportation connection from the island to the mainland is across bridge 24 which makes connection with existing Industrial Freeway 26. The high bridges 28 and 30 associated with the causeways 14 and 16, respectively, permit access to the inner harbors by large sea-going vessels. The smaller and lower inner bridges 32 and 34 permit flow of water to avoid ecological stagnation.

With reference to the island itself, the airport 36 is located at the outer end of the island which extends furthest into the ocean. The causeways 14 and 16 meet the island approximately in its center. The deep-water harbors 38 are located inside the causeway 16 so as to be shielded from rough ocean water. The industrial areas 40 and 42 are located between the airport region 36 and the inner region 44 of the island. At the innermost edge 44 of the island where the maximum height restrictions are not a serious problem and where the noise levels are relatively low, high-rise apartment buildings and office structures are located.

A small boat marina 46 is located inside the solid causeway 14 so that it is protected from adverse ocean conditions. Bay area 48 provides about 4,000 acres of protected pleasure boating bay area.

In the airport area per se the control tower is shown at 50 and the main terminal at 52. A freight terminal designated by reference numeral 54 is connected to the main terminal by passageway 56. Freeway access is provided on the surface of the main portion of the

60 causeway 14 so that it is protected from adverse ocean conditions. Bay area 48 provides about 4,000 acres of protected pleasure boating bay area.

65 In the airport area per se the control tower is shown at 50 and the main terminal at 52. A freight terminal designated by reference numeral 54 is connected to the main terminal by passageway 56. Freeway access is provided on the surface of the main portion of the

island as indicated by reference numerals 58. At point 60 the highway extends from the surface of the industrial area into an underground tunnel 62 which provides access to underground parking in the airport area.

Other features which may be noted in FIG. 2 of the drawings include the airport support and maintenance facilities 64, two instrument landing system runways 66, two non-instrument runways 68, associated taxiways 70, and two general aviation runways 72 approximately 4,000 feet in length. The local underground transportation link 73 interconnects the general aviation area with terminal 52.

The causeways 14 and 16 are provided with ocean-front beaches 74 and bay-front beaches 76, provided with parking facilities 78. These are interconnected by tunnels, and ramps permit easy access from the main traffic patterns on the freeways at the center of the causeways.

As shown in FIG. 1, the causeways 14 and 16 are provided with rock sand trap groins 86 where the beaches terminate discontinuously at the channels associated with the high bridges.

As an additional safety feature and to absorb high wave motion, the beaches 80 are provided in the vicinity of the airport. These beaches 80 provide "soft" landings under emergency conditions.

In the industrial area 42, both an underground rail yard 82 and a surface rail yard 84 may be provided.

FIG. 3 is a diagrammatic showing of the FAA regulations for landing elevations and the estimated sound or noise level in "perceived noise decibels," or PNDb. These diagrammatic indications of elevation and noise levels are superimposed on a view of the island and adjoining coastland. As mentioned above, in the areas 88 off the ends of the runways the maximum height gradually increases with distance from the end of the runway at a 50:1 ratio. Beyond 10,000 feet from the end of the runway in the areas designated 90 in FIG. 3 this ratio becomes 40:1. In directions away from the flight paths, the maximum limit is 150 feet for a distance of 13,000 feet from the center of the airport. This area of the island is designated by the reference numeral 92 in FIG. 3 and includes the principal portion of the industrial area of FIGS. 1 and 2. For an additional 7,000 feet the height limit is 20:1 and beyond this additional zone the limit is 500 feet. These additional areas of the island are designated 94 and 96 in FIG. 3.

In FIG. 3 the gradually curved lines 98, 102 and 104 represent noise levels in terms of perceived noise decibels (PNDb). The lines 98 are the 115 PNDb lines; the lines 102 represent the 100 PNDb lines; and contours 104 are the 75 PNDb lines. It is noted in passing that the 100 db contour is the historical litigation level and the 75 PNDb level is the level at which ordinary conversation is normally carried on. The 75 db contour would, in terms of the Community Noise Exposure Level (CNEL), be a noise level of 40 decibels, or db.

FIG. 4 is a schematic cross sectional view taken along lines 4—4 of FIGS. 1 and 2. In FIG. 4 the vertical scale has been expanded significantly as compared with the horizontal scale. To bring this out more clearly, it is noted that the total length of the island is approximately 5 miles or 26,000 feet. In FIG. 3 the airport terminal building 52 shows the general location of the airport

area on the outer end of the island. The dashed line 106 which starts toward the edge of the airport area represents a 150 foot maximum height for buildings near the airport. At point 108, 13,000 feet from the center of the airport, the 20:1 slope ratio starts, and extends, for an additional 7,000 feet. Beyond point 110, where the buildings could be 500 feet tall, no further definite height limitations are imposed.

In FIG. 4 the original ocean floor surface is indicated at 112. The outer perimeter of the landfill area is provided with a series of caissons 114, which terminate below the surface of the water. Inside the caissons which provide the greater portion of the periphery of the man-made island, landfill is provided. This may come from nearby shallow areas and from future dredging of the harbor, by way of specific examples. At the interface between the water and the island, beaches 80 are provided. As mentioned previously, these beaches serve to damp out high waves and provide emergency soft landing areas. In addition to the building height maximum contour levels shown by line 106, the contour of the surface of the landfill island may be seen from FIG. 4. In the airport area the nominal elevation may be about plus 30 feet above mean high tide level. In the main area of the island including the industrial and high-rise sections, the nominal elevation may be about plus 15 feet above the mean high tide level. The substantial discontinuity 116 between the airport level and the industrial area level is such as to permit easy entrance of vehicular traffic from surface highways in the industrial area 40 to the subterranean parking in the airport area.

Industrial buildings 118 are shown in this region 40 and high-rise buildings 120 are located at the inner end of the island. The extreme inner end of the island is bounded by the existing breakwater 18.

FIGS. 5 and 6 show cross sectional and plan views of causeway 14. The cross sectional view is taken along line 5—5 of causeway 14 with reference to FIG. 2 of the drawings. In FIG. 5 the caissons 122 form the outer boundary of the landfill area. The original ocean bottom is shown at 124 and the landfill is indicated by reference numeral 126. A sand surface 128 is provided for beach purposes on both the ocean and bay sides of the causeway.

In the plan view of FIG. 6 the main roadway or freeway 130 is clearly shown, as is the paved parking area 132. Suitable access roads, including ramps such as the offramp 134, are provided to permit bathers to reach the parking areas. Underpasses such as underpass 136 provide access to both the bay and ocean sides of the causeway and permit entrance to the main roadway 130 in either direction.

FIG. 7 is an enlarged cross sectional view which is interrupted at various points. As noted above, FIG. 7 generally parallels FIG. 4 but is on a larger scale. At the extreme right in FIG. 7 is the beach 80 which provides the interface between the ocean and the island. Above the beach area the additional slope 138 leads to the peripheral roadway 140. Inland from the roadway 140 a further slope 142 leads to the elevated airport area 36 which is at a nominal positive elevation of about plus 30 feet. In the balance of FIG. 7 other buildings which were shown in FIGS. 1 and 2 are shown again on a somewhat larger scale. These include the air cargo

complex 54 and the main terminal 52. At the far left end of the upper section of FIG. 7 is shown the discontinuity 60 between the airport area 36 and the industrial area 40. At this point the roadway 58 enters the surface vehicle access tunnel 62. Below the roadway is the rapid transit tunnel 64.

In the second section from the left in FIG. 7 the rapid transit vehicles 144 are shown following a path which brings them to the proper unloading stations within the underground airport terminal complex. In the central portion of FIG. 7 below the main passenger terminal 52 are included many underground facilities including the access facilities 146 to the terminal complex and other sub-surface facilities in area 148 which include baggage handling, parking and the like. Lower levels including area 150 are also provided for the rapid transit terminal, and storage facilities, by way of example.

FIG. 8 is a cross sectional view taken along lines 8—8 of FIG. 2. In FIG. 8 the water level 152 is shown with respect to the docks 154 associated with harbor facilities 38. Reference numeral 156 indicates, schematically, gantry crane facilities which may be associated with the dock facilities for the loading and unloading of ships. As shown in the right-hand upper section of FIG. 8, underground rail facilities 158 provide service to the industrial facilities 160 and the harbor facilities 38. The rapid transit facilities 162 may also extend through this area.

At the far right in the lower portion of FIG. 8 is shown the marina area 46 with suitable small boat handling gear 164 and appropriate retail store facilities 166.

The partial cross sectional view of FIG. 9 shows a highway 58 with underground rapid transit station facilities 168 located below the highway. The platforms 170 provide access to the rapid transit cars.

Now that the detailed description of the equipment and facilities has been completed, a recapitulation of some of the major features will be undertaken. In this connection attention is again directed to FIGS. 1 and 2 of the drawings. Several of the major features which have been considered and which will now be reviewed include (1) building height, (2) noise level, (3) water condition; and (4) ground or surface elevation. As discussed above, the building height restrictions increase going inland from the center of the airport, and the noise contours drop off rapidly. The industrial areas which normally do not include high buildings and do not require quiet may therefore be located toward the center of the island. In addition, the docking facilities and rail yards may occupy this intermediate area of the island. At the far inland area toward the coast, the high-rise residential and office structures are located.

The docking and marina facilities, being located in the inner portion of the industrial area, tie in with the water condition and exposure at various points along the perimeter of the island. Adjacent the open ocean, of course the waves will be higher and the water rougher. Within the protection of the solid causeway 16, however, the harbor operations may be conducted with little concern for damage to vessels which might otherwise occur. Alternative forms of roadway or causeway construction, such as the mounting of the roadway on pilings or concrete pins, would not provide this protection for the docking facilities. Further,

although the causeway is only located at a nominal elevation of between plus 15 to plus 30, or about plus 25 feet above mean high water, the beaches provide damping of wave action to insure the safety of vehicular traffic on the causeway.

It may also be noted that the residential high-rise area 44 is located adjacent the mainland for ready access to mainland attractions over bridge 24 and close to the marina 46 and sheltered beaches on the island or otherwise within the causeways 14 and 16. The arrangement of surface elevations readily permits highway traffic to be open to the daylight, thereby avoiding accidents, while the guided rapid transit facilities may be underground where their interference with surface and pedestrian traffic is minimal. It is once more noted that highway traffic located at a nominal elevation of 15 feet above mean high water permits easy access at several points including point 60 and point 172 to the underground airport parking areas.

The location of the beaches adjacent the causeways is most convenient in permitting easy access to these recreational areas without co-mingling with island traffic.

It is again noted that off-shore airports have been proposed heretofore and some early considerations have even been given to locating an airport in San Pedro Bay. Attention is particularly directed to the following articles dealing with this subject matter: "Dredging Faces Challenge from Jetports," *World Dredging and Marine Construction*, August 1969, pgs. 20 and 21; "Off-shore Airports," *Machine Design*, July 9, 1970, pgs. 20-26.

In conclusion, it is again emphasized that the orientation of facilities on an artificial off-shore transportation complex, so as to take full advantage of airport noise contours, maximum height limitations, surface contours and water conditions, is considered to constitute important features of the invention. Various minor changes in conformance with these principles are considered to be within the scope of the invention.

What is claimed is:

1. In an artificial island installation located along a section of coast generally paralleling the direction of prevailing winds:

an island extending from an inner region close to the coast to an outer region farthest removed from the coast, the main portion of said island having an elevation at a first level significantly above mean high tide;

an airport area including a plurality of runways extending generally parallel to the coast on the outer or farthest off-shore area of said island; said airport area being raised to a second level substantially above said first level, to provide easy underground access to said airport area from the main portion of said island and to provide supplemental protection against ocean surges;

at least one causeway extending from the coast to a central zone on said island between said outer and inner regions, said causeway including solid breakwater sections adjacent said island and at least one high bridge to permit access inside the causeway for ocean-going vessels;

deep water dock facilities located on said island between said causeway and the coast; and

high-rise buildings located on said island at its inner region.

2. An installation as defined in claim 1 wherein at least one additional causeway to said island is provided.

3. An installation as defined in claim 1 wherein said island is provided with highways and rapid transit facilities along said causeways interconnecting the coast to the island, said highways going underground upon entering said airport area.

4. An installation as defined in claim 1 wherein said airport includes separate passenger and freight terminal facilities, and wherein rail and highway access is provided to said freight facility, and wherein rapid transit and highway access is provided to said passenger terminal.

5. An artificial off-shore transportation and industrial complex located in proximity to the mainland comprising:

means forming an extended landfill area in a body of water adjacent a coast;

an airport located at the outer, farthest off-shore portion of said landfill area, said airport having noise contours decreasing and maximum building height contours increasing with increased distance from said airport, across said landfill area toward the coast;

high-rise buildings located on said landfill area on its portion closest to the coast where the height contours are at a maximum and the noise contours are at a minimum; and

industrial buildings having a lesser height within said height contours located on said landfill area between the airport and the high-rise buildings.

6. An off-shore complex as set forth in claim 5 wherein the surface of said landfill area has a contour which is substantially above the high water level of the body of water in the airport region and has a discontinuity to a significantly lower level which is still above high water level in the industrial area.

7. An off-shore complex as defined in claim 6 wherein the landfill surface contour has an interface with the surrounding water in the form of graduated beaches.

8. An installation as defined in claim 6 wherein transportation access facilities are at ground level in the industrial portion of said island and extend underground into said airport area.

9. A transportation complex as defined in claim 5 wherein landfill retaining structures terminating well below the surface of the water extend around the greater portion of the perimeter of said landfill area, beaches are provided between said retaining structures

10 and the main portion of said island, and wherein the surface elevation contour of said landfill area extends from below water level at said retaining structure, through water level at said beaches, to a first landfill level substantially above water level for the main portion of said landfill area, and to a second landfill level in the airport area significantly above said first landfill level, to permit easy underground access to the airport and to provide supplemental protection against weather at the exposed outer end of said landfill area.

15 10. An off-shore island complex as defined in claim 5 wherein causeways of solid construction adjacent said landfill area interconnect the mainland to the central region of said landfill area, and marine facilities are located on the portion of said landfill area toward the coast from said solid causeways where they are protected from rough open water.

11. A transportation complex as defined in claim 5 wherein combined freeway and rapid transit facilities provide access to said landfill area with the rapid transit facilities being located immediately beneath the freeway in some locations.

12. A transportation complex as defined in claim 5 wherein causeways of solid construction provide transportation access to said landfill area, wherein freeways are located on said causeways, and wherein bay-front beaches, ocean-front beaches, parking facilities, and sub-freeway tunnels are included on said causeways.

13. A transportation complex as set forth in claim 10 wherein a high bridge interrupts at least one of said solid causeways to provide access to said marine facilities by ocean-going vessels, and wherein additional bridges adjacent the coast link said solid causeways to the coast to permit free flow of coastal currents.

* * * * *
